United States Patent Office.

WILLIAM E. BARTON, OF EAST HAMPTON, CONNECTICUT.

Letters Patent No. 106,456, dated August 16, 1870.

IMPROVED MODE OF ATTACHING SLEIGH-BELLS TO STRAPS.

The Schedule referred to in these Letters Patent and making part of the same

I, WILLIAM E. BARTON, of East Hampton, in the county of Middlesex and State of Connecticut, have invented Improvements in Constructing and Attaching Sleigh-Bells, of which the following is a specification.

Nature and Objects of the Invention.

My invention consists, first, in constructing the top of the bell with lateral or radial angles or projections, which, while serving effectually to keep it from turning, will cause less injury to the strap than the longitudinal spurs or projections in common use.

My invention consists, second, in securing the bell upon its strap by means of a screw passing through and countersunk in the said strap, a threaded aperture in the top of the bell to receive the said screw, and projections of any suitable form upon the top of the bell to keep it from turning.

Description of the Accompanying Drawing.

Figures 1 and 2 are perspective views of two bells, illustrating the first part of my invention.

Figure 3 is a longitudinal sectional view of a bell and its attachments, illustrating the second part of my invention.

General Description.

In order to provide for securing the bell from turning, without marring the surface of the strap as much

as devices for this purpose commonly do, I cast the bell B with a boss, C, upon its top, having lateral projections or angles, c, of the form represented in figs. 1 or 2, or any non-circular shape, which will be adapted to become imbedded in the strap sufficiently to secure the bell against turning without puncturing or incising the strap.

The boss C may be made of a concave or cup-shape, to afford a better hold on the strap.

In the top of the bell B is an aperture, b, in which is tapped a thread, to receive a screw, D, which is passed through and countersunk in the strap A, a concave or flaring washer, E, being preferably interposed between the screw-head and the strap.

Claims.

I claim as my invention—

1. A bell, B, constructed with a flat boss, C, having lateral projections, c, adapted to secure the bell from rotation on its strap, substantially as set forth.

2. The combination of the screw D passed through and countersunk in the strap A, the bell B, having a threaded aperture, b, to receive the said screw and projections, to hold the bell from turning, as set forth.

W. E. BARTON.
